CHARLES A. HARPER, OF RAHWAY, NEW JERSEY.

Letters Patent No. 66,329, dated July 2, 1867; antedated June 24, 1867.

BOILER FOR HEATING WATER.

The Schedule referred to in these Letters Patent and making part of the same.

TO ALL WHOM IT MAY CONCERN:

Be it known that I, CHARLES A. HARPER, of Rahway, in the county of Union, and State of New Jersey, have invented a new and useful Improvement in Boilers for Heating Water; and I do hereby declare that the following is a full, clear, and exact description of the same, reference being had to the annexed drawings, making part of this specification, in which—

Figure 1 is a perspective view, and

Figure 2 is a vertical section.

The same letters are employed when referring to identical parts.

A is a boiler of any convenient form or desired size. The water contained in this boiler is heated by gas or coal, or in any convenient manner. The heat from the fire with the draught rises into the cylinder B, which is open below. This cylinder stands in the boiler, and is completely surrounded by water in contact with the heated sides of the cylinder B. Within this cylinder is placed a cylindrical heater, C, made tight and attached to the top of the cylinder B. Through this inner cylindrical heater passes a conical pipe, B', communicating with the fire below, and through a narrow aperture with the pipe E above. This pipe, passing through the boiler, discharges the smoke into the air. The cylindrical heater C thus arranged contains a narrow water-chamber, extending the entire length, and has a fire surface equal to its external area plus the area of the conical pipe B', which forms its inner surface. Two pipes D D' are placed so as to connect the internal cylinder C with the mass of water in the boiler. The pipe D' is placed near the bottom of the cylinder C, and the pipe D is placed near the top of the same. On account of its greater fire surface, as compared with the amount of water contained, the water will heat far more rapidly in the internal heater C than it will in the body of the boiler A. The heated water in the heater C being specifically lighter than that contained in the boiler will rise, passing through the pipe D, and to supply its place a current of water will flow into the heater below through the pipe D'. By this means a rapid circulation will be established through the heater, and the heat thus acquired being diffused through the boiler A will rapidly elevate its temperature.

I do not claim to have been the first to make use of this principle of circulation, but only the means by which it is produced.

What I claim as my invention, and desire to secure by Letters Patent, is—

The boiler A, having an internal flue or fire-chamber, B, surrounding the pipe-formed water-heater C, through which the water in the boiler circulates by means of pipes D D', said parts being constructed and arranged for use, substantially in the manner and for the purpose set forth.

In testimony whereof I have signed my name to this specification in the presence of two subscribing witnesses.
